INVENTOR

Michael Edward Wilson

UNITED STATES PATENT OFFICE.

MICHAEL EDWARD WILSON, OF DETROIT, MICHIGAN.

DIRECTION-INDICATOR FOR AUTOMOBILES.

1,397,666.

Specification of Letters Patent.

Patented Nov. 22, 1921.

Application filed August 4, 1921. Serial No. 489,770.

To all whom it may concern:

Be it known that I, MICHAEL EDWARD WILSON, a citizen of the United States, residing at Detroit, in the county of Wayne 5 and State of Michigan, have invented a new and useful Improvement in Direction-Indicators for Automobiles, of which the following is a specification, reference being had to the accompanying drawings in explaining 10 its nature.

My invention has for its object, improvements in the signaling device proper, of such direction indicators as employ a semaphore arm which in operation is displayed at different angles of inclination. The signaling arm is intended to be operated by an operating device placed conveniently to the vehicle operator, with which device it is connected by chain or other flexible transmission means. 15 The operating means employed should be of that class which provides different latching positions for each position of the semaphore arm and be preferably of that form shown in my application Serial Number 462,751 and 20 the invention consists in the improvements 25 particularly pointed out in the appended claims.

In the drawing the invention is shown as applied to a truck, the first figure being a 30 repetition as far as is applicable and as indicated by the first twelve figures of reference, of the first figure of the above named application. Referring to the drawings, 35 Figure 1, is a partial transverse section of a truck equipped with a device embodying my invention, Fig. 2, is an enlarged elevation of the signaling part of the device, Fig. 3, is a fractional repetition of Fig. 1, but with the signaling arm in the vertical position of 40 pose, a small portion being broken to show interior mechanism; Fig. 5, is a side view of Fig. 3, from which also a part is broken, and Fig. 4, is a further enlarged detail of 45 the latch parts, being a partial section on the indicated line of Fig. 5.

In Fig. 1, the parts of the vehicle indicated are: the goods body 1, the cab roof 2, the left hand wall of the cab 3, steering wheel 6, and seat 7. The signaling part, 12, 50 of the device I have shown mounted on the left hand part of the goods body 1, by the base 9 upon which it is carried. The operating device 21, secured to the cab wall on the inside in such position as to be reached 55 easily by the driver's left hand is that described and claimed in the former applica-

tion. Connection between is made by chain 10, or other flexible means of transmission, the chain being supported on pulleys 11, or pivots where it changes direction. 60

In use the signal arm takes the three significant positions shown in Fig. 1, and a vertical downward position of repose when not in use, not shown in Fig. 1, but indicated sufficiently in Fig. 3. The signal arm is 65 raised from its position to all three of the significant positions by the operating device 21, and retained in these positions by latching devices incorporated, and returned to the vertical position of repose by gravity upon 70 the operation of a trip device also incorporated therein.

Signal arms as previously constructed have in operation shown a tendency to rebound when falling by gravity into the position of repose particularly when a solid stop is used to limit the falling motion and while a friction or spring stop such as is used in my above application will eliminate the rebound, the use of such increases the effort 80 required to raise the arm at the first part of such movement.

In the present invention I overcome this disability by counterbalancing the arm so that the rebound will not be as severe and by 85 the use of a latch positively opposed to the direction of such rebound, which latch is automatically removed by the first operating strain of the transmitting chain.

The semaphore arm 12 I make of sheet 90 metal to resemble the human arm and hand in outline, and lengthwise of it I stamp corrugations, 13, to increase its stiffness. This arm is secured by screws 14, or otherwise to extensions 15, of an arm carrier 16, 95 pivoted upon the stud 17, formed integral with the metal base piece 9, which by its extended flange is secured as by screws 18, to any convenient part of the vehicle. On the side opposite to the arm, the body of the 100 arm-carrier is extended and thickened to form a counterbalance 19 of such weight as to nearly counterbalance the weight of the arm, leaving sufficient preponderance to the arm however to assure the arm taking the 105 vertical downward position when free to do so. On the back side of the arm carrier I form a circular flange 20, integral therewith and concentric with the stud 17, for the reception of the chain 10 by which the arm 110 is actuated. Between the extensions 15 the arm carrier is formed with a sector like

opening 21, leaving an outer bridge or strip 22, of arc shaped form between the extensions whose outline substantially continues the outline of the flange 20. Within the sector like opening of the arm carrier a post 23, formed integral with the base piece 9 extends through the body of the arm carrier. This post 23 is so placed upon the base that a flat side 24, makes contact with a radial side 25, of the sector like opening when the arm is in the vertical position of repose, and the opposite radial side of the opening is sufficiently removed from the first so that it does not strike the post when the arm is raised to its highest position. The arm in falling to its vertical position is arrested by the face 25, of the arm carrier striking the post.

Upon the back side of the arm carrier I 20 pivot a latch 26, upon a small stud 27, fast in the arm carrier, so located that the latch will engage the post 23 at a flattened face 28, provided upon the post, and the latch is provided with a spring 29, clamped solidly by one end in a slot in the latch the other end of which spring is strained by a pin 30, projecting from the back face of the bridge 22.

The transmission chain 10 actuating the arm passes about the flange 20 and has its end attached to the latch. The flange is interrupted at the latch location and the end 31, so formed near the latch is smoothly rounded to facilitate slipping of the chain over the same. In raising the arm from its vertical position the first strain put upon the chain by the operating device withdraws the latch from its position engaging the post, leaving the arm free to be raised as usual. Upon release of the operating device the chain is relieved of strain, the latch is then free to assume its position of engagement impelled by the spring and upon completion of the fall of the arm the latch engages the post and retains the arm in that position. As the operating device puts no strain on the chain when the arm is in its vertical position of repose the latch remains in its locking position and under the influence of the spring and the arm is retained in its vertical position held by the post from going any farther and by the latch from rebounding. And as only very light strain is required in the spring no noticeable effort is required to overcome same in starting to raise the signal.

What I claim and desire to secure by Letters Patent are:

1. In an automobile signal, a semaphore arm having an arm-carrier with divided extensions upon which the display signal is borne, and a base piece upon which the semaphore arm is pivoted having a stop post

projecting between the extensions of the arm-carrier. 65

2. In an automobile signal, a semaphore having an arm carrier with divided extensions upon which the display signal is borne, and a base piece upon which the semaphore arm is pivoted having a stop post projecting between the extensions of the arm carrier into the plane of motion of the arm carrier. 70

3. In an automobile signal, a semaphore arm having an arm-carrier upon which the display signal is borne, a base piece upon which the semaphore is pivoted having a stop-post projecting into the path of motion of the arm carrier, and a latch engaging the stop post; said latch carried by the arm-carrier and pivoted at a point thereon tangential to its engaging point with the post. 75 80

4. In an automobile signal, a semaphore arm having an arm-carrier upon which the display signal is borne, a base piece upon which the semaphore arm is pivoted having a stop post projecting into the path of motion of the arm-carrier, a latch engaging the stop post said latch carried by the arm-carrier, and a spring between the latch and 90 arm-carrier.

5. In an automobile signal, a semaphore arm having an arm-carrier upon which the display signal is borne, a base piece upon which the semaphore arm is pivoted having a stop-post projecting into the path of motion of the arm-carrier, a latch engaging the stop-post said latch carried by the arm-carrier, a spring between latch and arm-carrier, and an operating chain one end of 95 100 which is attached to the said latch.

6. In an automobile signal, a semaphore arm having an arm-carrier upon which the display signal is borne said arm-carrier also having an integral circular chain flange, a base piece upon which the semaphore arm is pivoted having a stop post projecting into the path of motion of the arm-carrier, a latch engaging the stop post said latch carried by the arm-carrier, a spring upon the latch, and an operating chain one end of 110 which is attached to the latch, the said chain also engaging the circular flange part of the arm-carrier.

7. In an automobile signal, a semaphore arm having an arm-carrier upon which the display signal is borne, a base piece upon which the semaphore arm is pivoted having a stop post projecting into the path of motion of the arm-carrier, and a latch engaging the stop-post said latch carried by the arm-carrier; the said arm-carrier also having a circular flange for an operating chain integral therewith and in the same plane with the latch. 115 120

MICHAEL EDWARD WILSON.
